Geo. P. Kimmel. Attorney

UNITED STATES PATENT OFFICE.

PETER PIMLOTT, OF BROOKLYN, NEW YORK.

CURTAIN-POLE.

1,401,727.

Specification of Letters Patent. Patented Dec. 27, 1921.

Application filed January 8, 1921. Serial No. 435,890.

To all whom it may concern:

Be it known that I, PETER PIMLOTT, a citizen of the United States, residing at Brooklyn, in the county of Kings and State 5 of New York, have invented certain new and useful Improvements in Curtain-Poles, of which the following is a specification.

This invention relates to curtain rods and more particularly to that class of adjustable, 10 sectional, supporting rods capable of being swung to various positions with respect to a wall or window to facilitate the hanging of a curtain, portières, or draperies, and likewise its removal therefrom.

One of the objects of the invention is 15 directed to a new and improved curtain rod and novel operating structure whereby a section of the same may be thrown at right angles to permit the hanging of window or wall coverings of various descriptions.

A very important object of the invention is to provide a construction of the above character which is rigid, durable, and easy 25 of construction, comprising comparatively few parts, inexpensive, easily assembled, and easily and readily operated when in position.

With these objects in view and others 30 which will be manifest and suggested as the nature and purpose of my invention are revealed in the following specification and drawing, wherein I have shown a practical, yet preferred embodiment thereof.

Figure 1 is a perspective view showing 35 the curtain rod partly broken away and in normal position.

Fig. 2 is a top plan view of a portion of the rod showing the operating mechanism.

Fig. 3 is a sectional view of the same 40 taken on the line 3—3 of Fig. 1.

Figs. 4 and 5 are detached views of the coöperating gearing for the sections of the rod and

Figs. 6 and 7 are perspective views of 45 holding brackets.

Referring to the drawing, wherein similar parts are designated by the same reference numerals throughout the specification, 50 5 designates the curtain rod or pole consisting of a long and short hollow section 6, 7 provided with machined or ornamental end knobs 8, 9 at their opposite ends to present an artistic appearance as is well 55 understood in devices of this construction.

The inner end of the shaft section 7 is pro-

vided with a hollow, machined element 10 which telescopically fits therein. A turning spindle 11 having a thumb nut 12^a thereon is positioned substantially centrally of the 60 element 10 and carries a mutilated gear 11^a and spacing collars 12^a, said gear being secured to and held in position on the said spindle by a screw 13 as clearly shown in Fig. 4 of the drawing. The end 14 of the 65 element 10 is preferably bifurcated to receive a coöperating gear member between the ears 15 which as shown are provided with alined apertures 16 for a connecting pin 16^a which securely retains the gears in 70 mesh.

The inner end of the longer section 6 is also provided with a telescopically positioned machined member 17 therein which is formed with a shoulder 18 abutting the 75 end of the section 6, said member 17 having a mutilated gear 19 formed integral therewith and coöperating with the first mentioned gear above referred to. A lug or stop 20 on the gear 19 prevents the same and 80 the section 6 from being thrown out of engagement with its complementary section, sufficient space being provided between the inner ends of the said sections to permit the longer section 6 to be thrown at right 85 angles from a wall or support as will be readily apparent from an inspection of Fig. 3.

In order to support the curtain rod or pole, I have shown and provided a wall 90 bracket 21 having a central web portion 22 on which is formed an integral ring 23 for holding the short section 7, said section being retained in position by a pin or screw 24 as clearly indicated in Fig. 1. A second wall 95 bracket 25 is also utilized to support the longer section, said bracket being substantially similar to the bracket 21 but provided with a substantially semi-circular member 26 with a hinged section 27 whereby the section 100 rod may be turned as above described and pointed out. The respective wall brackets are adapted to be secured to a support by any form of suitable fastening elements for which apertures 28 are provided in the respective wall brackets as shown in Fig. 1 of the drawing.

In the actual operation of the device, it will be readily seen that after the sectional rod is placed in position on the wall supporting brackets and it is desired to place a curtain, portière or drapery thereon, the 110

spindle 11 is turned to the right and the co-operating gears 11^a, 19 of the respective sections will throw the longer section at right angles to the wall whereupon it is again replaced in the hinged supporting bracket 25 in the well known manner. From the above construction, it will be readily apparent that I have provided a novel curtain rod, which is extremely simple and highly efficient for its intended use, practical and capable of being manufactured at a comparatively low cost and otherwise meeting the requirements of fixtures of this character.

In the accompanying drawings, I have illustrated my invention embodied in one form by way of example, and which in practice has been found to be highly satisfactory in obtaining the desired results. It will be obvious, however, that other embodiments may be adopted and that various changes in the details of construction may be resorted to by those skilled in the art without departing from the spirit and scope of the invention. It is furthermore understood that the invention is not necessarily limited or restricted to the precise elements shown except in so far as such limitations are specified in the subject matter being claimed.

Having shown and described my invention, what I now claim as new and desire to secure by Letters Patent is:—

1. In a fixture of the class described in combination with supporting brackets, a sectional rod, gearing carried by the respective sections, and means for operating said gearing to turn one section with respect to the other.

2. In a fixture of the class described in combination with supporting brackets, a sectional rod, coöoperating gears carried in the inner ends of the respective sections, and a spindle for actuating one of said gears to turn one section with respect to the other.

3. In a fixture of the class described in combination with supporting brackets, a sectional rod, separable members having mutilated coöperating gears positioned in the inner ends of said sections, and a spindle

carried by one of said sections for operating one of said gears to turn the other section in various angular positions.

4. In a fixture of the class described in combination with supporting brackets, a rod having a long and short complementary section, one of said sections being fixed to a bracket, separable members having mutilated coöperating gears positioned in the inner ends of the respective sections, and a turning spindle for actuating the gear in the fixed section whereby the other section may be turned at right angles.

5. In a fixture of the class described in combination with supporting brackets, a rod having a long and short complementary section, one of said sections, being fixed to a bracket, separable members having mutilated gears positioned in the inner ends of the respective sections, a turning spindle for actuating the gear in the fixed section, whereby the other section may be turned at various angular positions with respect to the other section, and a lug or stop member formed with one of said gears for limiting the movement of the movable sections.

6. In a fixture of the class described in combination with supporting brackets, a sectional rod, and means for turning one of said sections at an angle with respect to the other, said means comprising a rotatable element supported in the inner end of one of said sections.

7. In a fixture of the class described in combination with supporting brackets, a sectional rod, toothed gears mounted in the inner ends of the respective sections and means for rotating one of said gears to move one section angularly with respect to the other.

8. In a fixture of the class described in combination with supporting brackets, a sectional rod and means carried thereby for turning one of said sections in various angular positions with respect to the other.

In testimony whereof I affix my signature hereto.

PETER PIMLOTT.
